UNITED STATES PATENT OFFICE

WILLIAM B. SKINKLE, OF STEUBENVILLE, OHIO.

CLAM-SHELL BUCKET.

No. 835,567.

Specification of Letters Patent.

Patented Nov. 13, 1906.

Application filed March 19, 1906. Serial No. 306,774.

To all whom it may concern:

Be it known that I, WILLIAM BALDWIN SKINKLE, a citizen of the United States, residing at Steubenville, Jefferson county, Ohio, have invented certain new and useful Improvements in Clam-Shell Buckets, of which the following is a specification, that will enable those skilled in the art to which the invention pertains to make and use the same, reference being had to the accompanying drawings, which form a part thereof.

My invention relates to that class of device commonly known as "clam-shell buckets" or "grab-buckets," adapted to drop and scoop or dig into masses of material—such as coal, ore, earth, &c.—and to detach and remove large bodies of such material from the original masses; and this description and the accompanying drawings show the at present preferred form of embodying the principles of my invention in a working device that will be cheap to make, easy to repair, and economical to operate.

In the drawings, Figure 1 is a side elevation of a clam-shell or grab bucket embodying the principles of my invention, the scoop members being shown by full lines in their open position and the connected parts in corresponding positions, while by dotted lines 25 the scoop members and their connected parts are shown in their closed positions. Fig. 2 represents a vertical longitudinal section of the same, taken on the lines 2 2 of Figs. 3, 4, and 5, the scoops being closed. Fig. 3 represents a vertical transverse section on the line 3 3 of Fig. 2. Fig. 4 is a general plan or top view, and Fig. 5 a horizontal section on the lines 5 5 of Figs. 2 and 3.

In a general way my device consists of a pair of swinging buckets or scoops A and A', suspended from a frame or head B by links C C' and D D', and the whole is suspended from suitable overhead supports by flexible chains, cables, or ropes E E' and F F'.

For the purpose of closing the buckets with power and lifting the entire load I prefer to use chains E E', while for the purpose of opening the buckets and lowering the device I prefer to use lighter ropes or cables F F', as will hereinafter be explained.

The scoops A A' are preferably made from single steel sheets bent to the shape shown, and they are provided with round cross-bars

or shafts a a', mounted at their ends in blocks a² and a³, which reinforce the shell of the 55 buckets at the bearing-points of the shafts.

The head or frame B is preferably made with a top plate b and side plates b', suitably joined at their meeting edges, the top plate having a square central aperture b² for the 60 passage of the lifting-chains. The side plates are reinforced by flat bars b³, which form bearings for round bars or shafts G and D², which extend across within the frame.

At each side of the frame are secured plate-lugs b⁴, which form bearings for the ends of 65 round bars or shafts C², which extend across the frame above its top.

Mounted on the top of the frame near each of its corners are brackets H, which carry 70 guide-sheaves h, and near each side at the center of the frame are secured other double brackets H', carrying guide-rollers h'. There is also on top of the frame at its center a double bracket I, which supports chain-sheaves i i' in proper relation to the chain-aperture b², and it also carries a pair of idle chain-sheaves i² and i³, which oppose the sheaves i and i', respectively.

The abutting ends of the scoops are supported 80 from the frame by the links C and C', which are pivoted at their upper ends on the shafts C² of the frame and at their lower ends on the shafts a of the scoops. The lower ends of the links are provided with outside forks c, 85 which are riveted to the main bodies of the links and straddling the upper edges of the scoop give them double bearings on the shafts a.

The outer ends of the scoops are supported 90 from the frame by links D D', pivoted at their upper ends on the shafts D² of the frame and at their lower ends on the shafts a' of the scoops.

The relative location of the shaft-axes C² 95 and D² on the frame and of the shaft-axes a and a' in the scoops, together with the lengths of the links C and D, are calculated to impart to the scoops the most desirable path of movement to perform their functions.

To open the scoops when they are being lowered, four cables or ropes F F and F' F' are employed, one at each side of each scoop. The lower ends of these cables are secured to the scoop-shafts a, from whence they pass to 100 the guide-sheaves h at the outer corners of

the frame and thence to the guide-sheaves h' of the double brackets at the center of the frame. It will be observed that when the chains are slackened and the entire weight of 5 the device is thrown upon these cables F and F' they pull the scoops apart to the positions shown in Fig. 1.

In order to close the scoops and bring them together with a powerful bite without 10 the use of special levers, gears, differential pulleys, or other such forms of power mechanism, I arrange and utilize the lifting-chains themselves to perform this function by passing them around series of sheaves on the 15 shafts a' of the scoops and on the shafts G of the frames after the manner of the well-known block and tackle.

The lower end of each chain E is secured by a link e to the shaft G of the frame, from 20 whence it passes around a series of chain-sheaves e' on the shaft a' of the scoop and a series of chain-sheaves e^2 on the shaft G of the frame alternately, and thence from the last of the sheaves e^2 to guide-sheaves i on the 25 top of the frame, and thence to the winding drum or power mechanism. (Not shown in the drawings, but well understood in the art.) Thus by the addition of a few rotatable chain-sheaves independently mounted on the cross- 30 shafts a' and G and the employment of the lifting chains or cables directly upon these sheaves I am enabled to dispense with special forms of power mechanisms and with my block-and-tackle arrangement to produce a 35 powerful closure of the scoops.

The simplicity of this device, the cheapness of its construction, and the readiness with which it may be repaired are the special features of commercial value claimed for it.

40 In practical construction as now designed for large and heavy work these scoops are each about six feet wide and five and one-half feet long, or, say, eleven feet long over both scoops when closed, as shown in Fig. 2.

45 The other parts are proportionately large, the head or frame being ten feet long by five feet wide and five feet deep. Such a clam-shell bucket is capable of taking up many tons of earth, ore, coal, or other such material at each operation.

50 Other modes of applying the principle of my invention may be employed instead of the one explained herein and illustrated by the drawings, which is the preferred form at this time, such changes being made as regards the mechanism herein disclosed, provided the means stated by any one of the following claims or the equivalent of such stated means be employed.

60 Having thus described my invention, what I claim as new and useful, and desire to secure by Letters Patent, is—

1. In a clam-shell bucket, the combination 65 of a frame, a pair of scoop members link-supported beneath the frame and adapted to

oscillate through suitable arcs, shafts on the frame carrying a series of sheaves and shafts in each scoop member also provided with a series of sheaves opposed to those on the frame-shafts, with a pair of lifting-chains 70 each secured at its lower end and passing alternately around the sheaves of its opposed series and thence to a guide-sheave on top of the frame, whereby draft on the chains will first close the scoop members with great 75 power and then lift the entire apparatus, substantially as set forth.

2. In a clam-shell bucket, the combination of a frame, a pair of scoop members link-supported beneath the frame and adapted to 80 oscillate through suitable arcs, shafts on the frame and a shaft in each scoop member provided with opposing sheaves, a pair of lifting-chains each secured at its lower end and passing alternately around the sheaves of its opposed series on the frame and scoop-shafts and thus adapted to close the scoops with great power, with scoop-opening cables attached to the scoop members and passing thence to guide-sheaves on the outer corners 90 of the frame and thence to guide-sheaves at the center of the frame, substantially as set forth.

3. In a clam-shell bucket, the combination of a frame, a pair of scoop members adapted 95 to swing in arcs below the frame and each suspended from the frame by a pair of side links pivoted on a cross-shaft located at the inner end of the scoop near its top edge and on a shaft located on the top of the frame 100 approximate the center thereof, and by another pair of side links pivoted on a cross-shaft located at the outer end of the scoop at its top edge and on a shaft located on the frame near its outer end and near the top, a 105 series of guide-sheaves on said outer scoop-shaft; shafts located near the lower edge of the frame and provided with sheaves opposed to those on the outer scoop-shafts, with a pair of lifting-chains secured at their lower 110 ends and each passing alternately around its opposed series of sheaves and thence to a guide-sheave on the top of the frame, substantially as set forth.

4. In a clam-shell bucket, the combination 115 of a frame, a pair of scoop members adapted to swing in arcs below the frame and each suspended from the frame by a pair of side links pivoted on the frame and on a cross-shaft located at the inner end of the scoop 120 near its top edge, and by another pair of side links pivoted on the frame and on a cross-shaft located at the outer end of the scoop at its top edge, a series of guide-sheaves on said outer scoop-shaft; shafts mounted in the 125 frame near its lower edge and provided with sheaves opposed to those on the outer scoop-shafts, with a pair of lifting and closing chains secured at their lower ends and passing alternately around its opposed series of 130

sheaves and thence to guide-sheaves on the top of the frame, and scoop-opening cables attached to the scoops and passing thence to guide-sheaves on the outer ends of the frame and thence to guide-sheaves near the center of the frame, substantially as set forth.

5 In testimony whereof I have signed my

name to this specification in the presence of two subscribing witnesses.

WILLIAM B. SKINKLE.
